Issue 11-11-8

UNITED STATES PATENT OFFICE.

SIGMUND FEUST, OF NEW YORK, N. Y.

DESIGN FOR TOY BUREAUS, &c.

Specification forming part of Design No. 7,753, dated September 8, 1874; application filed July 18, 1874.
[Term of Patent 7 years.]

To all whom it may concern:

Be it known that I, SIGMUND FEUST, of the city, county, and State of New York, have invented a Design for Toy Bureau or Side-board, of which the following is a specification:

The nature of my design is fully represented in the accompanying photographic illustration, to which reference is made.

It consists mainly in the special configuration of the upper part of the bureau or side-board, and the ornamentation of the front of the drawers by means of oblong panels in high relief.

A represents the upper or wall part, arranged symmetrically around a central looking-glass, with inclined corner-pieces B, two or more brackets, C, and suitable top or crown piece

D. The upper part widens toward the lower drawer or shelf part. Oblong rectangular panels in high relief are applied to the front of the drawers, as shown. The same will, in practice, be veneered or otherwise ornamented, to give a finished appearance.

What I claim is—

The design for a toy bureau, whose upper part has the brackets C, inclined corner-pieces B, and crown D, arranged around the mirror-space and the body or lower part, ornamented by high-relief panels of oblong rectangular form, applied to the front of the drawers, as shown.

SIGMUND FEUST.
